UNITED STATES PATENT OFFICE.

CLINTON E. WALTON, OF LIVINGSTON, MONTANA.

FLASH-LAMP.

1,284,502.

Specification of Letters Patent. Patented Nov. 12, 1918.

Application filed August 31, 1917. Serial No. 188,181.

To all whom it may concern:

Be it known that I, CLINTON E. WALTON, a citizen of the United States, residing at Livingston, in the county of Park, State of Montana, have invented certain new and useful Improvements in Flash-Lamps; and I do hereby declare the following to be a full, clear, and exact description of the invention, such as will enable others skilled in the art to which it appertains to make and use the same.

This invention is an improvement in lamps and has particular reference to an electric flash lamp.

15 An object of the invention is to provide a lamp of simple and inexpensive construction which is not only capable of being used as a pocket flash light but may also be supported from a suitable portion of a garment 20 or may be attached to vehicles of different kinds.

25 The inventive idea involved is capable of receiving a variety of mechanical expressions, one of which, for the purpose of illustrating the invention, is shown in the accompanying drawing, wherein:—

Figure 1 is a front elevation of the lamp constructed in accordance with the invention.

30 Fig. 2 is a side elevation of the lamp partly in section.

Fig. 3 is a fragmentary longitudinal vertical section.

Fig. 4 is a perspective view of one of the lamp supporting brackets.

A preferred form of the invention is illustrated in the accompanying drawing wherein the numeral 5 indicates the casing or body portion of the lamp which incloses a dry cell 6 having the contacts 7 and 8 extending therefrom. Any well known form of dry cell may be used and it will be readily apparent that the same may be replaced whenever desired. The casing 5 is provided upon 15 the rear thereof with an attaching clamp 9 having one end secured to the casing by means of fasteners 10 and provided intermediate its ends with a bent portion 11 adjacent which projects a lug 12 adapted for engagement with the top of the cover 13 whereby to aid in retaining said cover in closing position. A portion 14 of the clamp formed by bending the same at 11 is provided adjacent its upper end with an aperture 15 which extends through an enlarge-

ment 16, said opening being screw-threaded to receive a screw carried by a vehicle such as a bicycle or motorcycle whereby the lamp may be attached thereto. The portion 14 is further provided with a plurality of projections or spurs 17 which are adapted to engage the cloth of a garment whereby to securely retain the lamp in an adjusted position. When it is desired to carry the lamp about in the hand, a bail 18 may be employed the ends of which are bent in and adapted to detachably engage the sockets 19 formed adjacent the top and at the ends of the cover 13.

One end of the cover 13 is preferably provided with a vertically disposed slot 20 in which is adjustably mounted the contact 21 in the form of a screw secured in position by means of a nut 22, said contact being adapted to engage the contact 7 when the cover is in closing position. Centrally disposed in the top of the cover 13 is a second contact 23 in the form of a screw, the inner end of which is adapted to engage the contact 8 when said cover is closed and said contact 23 is insulated from the cover by means of the bushing 24. The contact 23 is held in position by means of nuts 25.

A pair of oppositely disposed lamp supporting brackets 26 and 27 are pivotally mounted upon the contact 23 and the pivoted end of the bracket 27 is in engagement with the top of the cover 13 while the adjacent end of the bracket 26 is separated from the end of the bracket 27 by the insulation 28. In order to aid in retaining the insulation 28 in place the adjacent end of the bracket 27 is provided with a projection or lug 27' which bites into the under surface of the insulation but which does not engage the bracket 26.

A reflector casing 29 is pivotally mounted between the free ends of the brackets 26 and 27 by means of the pivot pins 30 and 31 disposed at diametrically opposite points 100 on the casing 29 and extending horizontally therefrom whereby the casing will swing about a horizontal axis in addition to being adjustable about a vertical axis formed by the pivoting of the brackets 26 and 27 on the contact 23. The pivot 30 is insulated from the reflector casing 29 and has mounted thereon one end of a curved arm 32 partially wrapped with insulation 33 and having its free end normally spaced from the adjacent 110

end of the lamp socket 34 carrying the small lamp 35, said free end of the arm 32 being adapted for electrical contact with the end contact of said socket 34 when said arm is 5 pressed by a finger of the operator. The casing 29 is in electrical engagement with the bracket 27 through the pivot 31 so that the current from the cell 6 will flow through the contact 21, cover 18, bracket 27, casing 10 29 and lamp 35. When the arm 32 engages the socket 34, the current will then flow through said arm to the pivot 30 and from thence downwardly through the bracket 26, contact 23 in engagement with said bracket, 15 and then through the contact 8 of the cell 6.

What is claimed is:—

1. In a flash lamp, the combination of a cell containing casing, a removable cover therefor, contacts carried by said cover and 20 in circuit with the cell in said casing, supporting brackets pivoted upon one of said contacts and insulated from each other, one of said brackets having electrical engagement with said cover and the other with said 25 contact, a reflector casing pivotally mounted between said brackets and having a lamp socket therein, and a resilient contact arm carried by one of the pivots of said casing and adapted for electrical engagement with 30 said lamp socket and said other bracket whereby to close the circuit.

2. A flash light comprising a cell containing casing, a removable cover therefor, a

contact vertically adjustable in one end of said cover adapted to engage one of the contacts of a cell in said casing and having electrical contact with said cover, a second contact disposed vertically in the top of said cover and having engagement with the other contact of said cell and being insulated from 35 said cover, a pair of supporting brackets 40 pivotally mounted upon said second contact, one of said brackets being insulated from said contact and having electrical engagement with said cover, the other bracket being 45 insulated from the first named bracket and having electrical engagement with said second contact, a lamp supporting casing pivotally mounted on horizontal pivots between 50 said brackets, said casing having electrical contact with the first named bracket and insulated from the second named bracket, and a resilient contact arm adapted for engagement with a lamp in said lamp casing and carried by one of the pivots of said lamp 55 casing and having electrical connection with the second named bracket whereby a circuit may be closed through said cover, supporting brackets, and lamp casing.

In testimony whereof, I affix my signature 60 in the presence of two witnesses.

MR. CLINTON E. WALTON.
